(57) **CLAIM**

I claim an ornamental design for an illumination device, as shown and described.

DESCRIPTION

FIG. 1 is a perspective view of a illumination device, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a side perspective view thereof.

The dashed lines are included for illustrating interior and/or environmental structures and form no part of the claimed design.

1 Claim, 6 Drawing Sheets

FIG. 1

FIG. 4

FIG. 5

FIG. 6

FIG. 7
